UNITED STATES PATENT OFFICE.

LAWRENCE H. JENSEN, OF ST. CHARLES, ILLINOIS.

PUMP.

1,244,053.

Specification of Letters Patent.

Patented Oct. 23, 1917.

Application filed October 12, 1916. Serial No. 125,205.

To all whom it may concern:

Be it known that I, LAWRENCE H. JENSEN, a citizen of the United States, and a resident of St. Charles, county of Kane and State of Illinois, have invented certain new and useful Improvements in Pumps, of which the following is a specification.

My invention relates to portable pumps and more particularly to manually operated piston pumps for inflating vehicle tires, small pressure tanks and the like.

One of the objects of my invention is the provision of a pump of this character that will combine all the advantages of a double cylinder pump in a single cylinder without the employment of additional labor on the part of the operator. Another object is the provision of a pump wherein the cylinder piston is actuated by a supplemental or auxiliary plunger disposed adjacent and parallel thereto. Another object of my invention is the provision of a pump of this character wherein the initial movement of the pump piston, during which the compression in the cylinder is only slight, will be faster than the movement of the operating plunger, while the movement of these respective elements during the intermediate or medium compression period will be substantially equal and uniform, and the final movement will be such as to cause the piston to travel more slowly than the actuating plunger.

I prefer to accomplish the divers objects of my invention by substantially the means and in the manner hereinafter fully described and as more particularly pointed out in the claims, reference being had to the accompanying drawings, forming a part of this specification, wherein:

Figure 1 is a vertical side elevation of a pump constructed in accordance with my invention, showing the relative position of the divers elements when the pump piston is fully elevated about to start the compression operation.

Fig. 2 is a view similar to Fig. 1, showing the disposition of the respective parts when the pump piston is in an intermediate position.

Fig. 3 is a view similar to Fig. 1, showing the position of the respective parts when the pump piston is fully depressed.

Fig. 4 is a vertical elevation of my invention at substantially a right angle to Fig. 3, with the pump piston fully depressed.

Referring to the drawings wherein simi-

lar reference characters are employed to designate the respective parts throughout the figures, it will be observed my pump preferably comprises the usual cylinder 5 mounted vertically upon a suitable base or foot-plate 6 and provided with a longitudinally reciprocable piston rod 7, to the lower inner end of which latter a piston head 8, of usual type, is secured. The upper end of the cylinder is preferably closed by a suitable cap 9 that affords an upper bearing or guide for the piston rod 7, and is preferably extended laterally beyond said cylinder, as shown in the drawings, to provide a guide 10 for the operating handle, as will be herein-after more fully described. Mounted on the foot-plate 6, adjacent to and parallel with the axis of the cylinder 5, is a suitable rod 10 that extends upwardly toward and terminates adjacent the extension of said cap 9. The operating plunger 11 is hollow or cylindrical and surrounds this rod 10 and passes through a suitable bearing in the extended portion of the cap 9, and its lower end has secured thereto a suitable L-shaped bracket 12, the longer member whereof projects upwardly a short distance parallel with said plunger. A suitable bell-crank lever is pivotally mounted upon the upper end of this bracket 12 so that the substantially horizontal arm 13 of said bell-crank extends past the operating plunger toward and alongside the cylinder, and the substantially vertical arm 14 of said bell-crank extends down alongside the vertical member of said bracket. This bell-crank is preferably made of one piece of metal that is provided with an arched portion 15, through which the pintle 16 passes to mount it upon the bracket 12, and the metal is then curved laterally and outwardly to form the arm 13 above mentioned.

The outer or movable end of the arm 13 is pivotally connected to the lower end of a vertically disposed link or pitman 17, that extends upwardly and terminates adjacent the upper end of the piston rod 7 in a laterally bent portion 18, that provides means whereby said link is secured to the upper end of said piston rod 7. The lower end of the vertical arm 14 of the bell-crank is provided with an extension 19 that engages a substantially vertically disposed cam-bar or guide 20 secured to and extending between the foot-plate 6 and the cap 9 of the cylinder.

A suitable handle 21 is secured to the upper end of the operating plunger 11 and when the latter is reciprocated in an up-and-down movement, the bracket 12 is likewise raised and lowered, and through the connecting arm 13 and pitman 17 is adapted to reciprocate the piston rod 7 inside the cylinder. In a pumping operation it is usually the practice of the operator to exert 10 the greatest labor during the latter portion of the downward movement of the piston and it will be observed when this is done the bell-crank and connecting parts will be in the position shown in Fig. 1 of the drawings. As there is but slight compression 15 within the cylinder during the initial movement of the piston downwardly, it is desirable and easier to move the latter quickly or at a greater speed than the speed at 20 which the operating plunger travels. During the intermediate portion of the movement of the parts, when the air in the cylinder is under greater or increasing pressure, the cam rod 20 retards the movement 25 of the piston and permits the same to travel at a uniform speed with the plunger. Toward the end of the downward movement of the piston, the greatest compression is exerted against the air in the cylinder and 30 during this latter movement the piston travels at a slower speed than the operating plunger, owing to the fact that the bell-crank arm 14 is approaching the cylinder at its lower movable end and is consequently 35 elevating the free movable end of the arm 13. This causes a retarded movement or a movement of the piston slower than the operating plunger until the end of the pumping action is completed, thus permitting 40 the operator to obtain a greater compression with comparatively less exertion than is possible with a single cylinder pump of the ordinary type.

While I have herein disclosed certain specific means for carrying out my invention, 45 it, of course, will be obvious to others familiar with the art to which my invention pertains, that modifications or refinements thereof are possible without materially departing from the spirit of my invention. I therefore desire it understood that all such changes are contemplated as included within the scope of my invention as expressed in the appended claims.

55 What I claim is:—

1. A pump comprising a cylinder, a piston operable therein, a member for actuating said piston, a lever carried by said member and operatively connected to said piston, and 60 means for imparting a movement to said lever independently of its movement with said member.
2. A pump comprising a cylinder, a piston

operable therein, a member for actuating said piston, a lever carried by said member 65 and operatively connected to said piston, and a cam member adapted to engage a portion of said lever whereby a movement is imparted to said lever independently of its movement with said member. 70

3. A pump comprising a cylinder, a piston operable therein, a member for actuating said piston, a lever carried by and movable with said member and operatively connected to said piston, a lever carried by and movable with said member, a link connecting 75 said lever to said piston, and means for imparting a movement to said lever independently of its movement with said member.

4. A pump comprising a cylinder, a piston 80 operable therein, a reciprocable plunger for actuating said piston, a bell-crank carried by said plunger one arm whereof is operatively connected to said piston, and means engaging the opposite arm of said bell-crank 85 whereby a movement is imparted thereto independently of its movement with said plunger.

5. A pump comprising a cylinder, a piston operable therein, a reciprocable plunger for 90 actuating said piston, a bell-crank carried by said plunger, a link operatively connecting one arm of said bell-crank to said piston, and means engaging the opposite arm of said bell-crank whereby a movement is imparted 95 thereto independently of its movement with said plunger.

6. A pump comprising a cylinder, a piston operable therein, a member for actuating said piston, a lever carried by and movable with 100 said member and operatively connected to said piston, a lever carried by and movable with said member, a link connecting said lever to said piston, and a cam rod adapted to engage a portion of said lever whereby 105 a movement is imparted to said lever independently of its movement with said member.

7. A pump comprising a cylinder, a piston operable therein, a reciprocable plunger for 110 actuating said piston, a bell-crank carried by and movable with said plunger, a link connecting one arm of said bell-crank to said piston, and a cam rod adapted to engage the 115 opposite arm of said bell-crank whereby a rocking motion is imparted to said bell-crank independently of its reciprocation with said plunger.

Signed at Chicago, county of Cook and State of Illinois, this 10th day of October, 120 1916.

LAWRENCE H. JENSEN.
